E. A. WHEATON

OPEN HEARTH FURNACE

Filed June 21, 1921

UNITED STATES PATENT OFFICE.

EZRA A. WHEATON, OF SPARROWS POINT, MARYLAND, ASSIGNOR TO BETHLEHEM STEEL COMPANY, OF BETHLEHEM, PENNSYLVANIA, A CORPORATION OF PENNSYLVANIA.

OPEN-HEARTH FURNACE.

Application filed June 21, 1921. Serial No. 479,342.

To all whom it may concern:

Be it known that I, EZRA A. WHEATON, a citizen of the United States, and residing at Sparrows Point, county of Baltimore, State 5 of Maryland, have invented certain new and useful Improvements in Open-Hearth Furnaces, of which the following is a specification.

The present invention relates to open 10 hearth furnaces and more particularly to an improved means for supporting the roof thereof against outward movement at its lateral edges. Heretofore the lateral thrust at the edges of the roof has been taken up 15 by channel beams mounted wholly within the side walls of the furnace. With this construction it is found that the channels and particularly the lower flanges thereof become overheated causing the same to warp 20 and buckle permitting the roof to collapse, even long before the furnace has been rendered inoperative by burning out the bricks or lining thereof.

It is the principal aim of the present invention to overcome the defect mentioned 25 above and to this end the channels or beams supporting the roof against lateral thrust are disposed in such a manner that they are not subjected to overheating. In the form 30 shown herein channel beams are employed and are positioned so that they lie entirely without the structure of the vertical walls of the furnace.

Other objects and features of novelty will 35 be apparent from the description taken in connection with the drawings, in which:

Figure 1 represents a vertical section of 40 Figure 2 is a partial section 2—2 of the open hearth furnace shown in Fig. 1;

Figure 3 is a vertical section of an open 45 hearth furnace of the type now generally used.

Referring to the drawing it will be noted 50 that my improved furnace is comprised essentially of a front wall 1, a rear wall 2, two end walls, not shown, a hearth 3, and an arched roof 4, the walls and roof being made 55 of any suitable refractory material. The vertical component of the weight of the roof is transmitted to the walls by the skew-back 60 5, and the horizontal thrust of the arch is transmitted by the skew-back bricks 5 to the

steel channels 6, and thence to the steel stays 55 7, which are suitably tied to the foundation structure at their lower ends, and cross-connected at their upper ends by the tie-rods 8. It will be observed that in my improved open hearth furnace, as illustrated in 60 Figures 1 and 2, that the channels 6 are fitted into recesses in the stays 7, and that the lower flanges of the channels 6 are wholly without the wall structure, whereas, in the open hearth furnace of the type now 65 generally used (see Figure 3), the channels 6' are not fitted into the stays 7, but are flush with the outer surfaces of the front and rear walls, the lower flanges of the channels being incorporated in the wall structure. 70

In practice it is found that the refractory lining of the upper portion of an open hearth furnace burns away first at the junction of the roof and wall in the manner indicated by the line 9 in Figure 1. If this 75 burning is noted in time, it is customary to permit the furnace to cool off and to replace only the burnt brick. However, if the skew-back bricks are burned, a replacement of a portion of the roof is very difficult and not 80 always possible, and under such circumstances it is very often necessary therefore to replace the entire roof. In the type of furnace illustrated in Figure 3, the burning of the refractory lining at the junction of the 85 roof and wall also results in serious overheating of the channel, particularly along its lower flange. This overheating causes the channel to warp and bulge out laterally between adjacent stays, thus permitting the 90 skew-back bricks to slip and the roof to collapse even before a serious extent of burning is noted.

It will be observed from Figures 1 and 2 that in my improved design the lower flange 95 of the channel 6 is entirely removed from the brick-work structure and is exposed along its lower face to the atmosphere, thus facilitating heat radiation and preventing the tendency to warp. Moreover, the withdrawal of the lower flange of the channel from the brick work structure also results in the partial withdrawal of the skew-back 100 bricks. The line 10, Figure 3, is of the same contour, and indicates the same extent of 105 burning as the line 9, Figure 1, and it will be observed that for the same extent of burning the skew-back brick in Figure 3 is con-

siderably corroded, while the skew-back brick in Figure 1 is not corroded. The improved structure therefore tends to prevent burning of the skew-back bricks and thus 5 facilitates replacement of a portion of the roof only when burning is noted.

Having described my invention what I claim as new and desire to secure by Letters Patent is:

- 10 1. In an open hearth furnace the combination of stays, a vertical wall, an arched roof, a skew-back brick between said wall and said roof, said skew-back being laterally supported by a channel fitted into recesses in 15 said stays.
2. In an open hearth furnace the combination of stays, a vertical wall, an arched

roof, a skew-back brick between said wall and said roof, said skew-back being laterally supported by a channel fitted into recesses in 20 said stays, the lower flange of said channel being disposed wholly without the structure of said vertical wall.

3. In an open hearth furnace the combination of stays, a vertical wall, an arched 25 roof, a skew-back brick between said wall and said roof, said skew-back being disposed in and laterally supported by a channel, the major portion of the lower flange of said channel being disposed wholly without the 30 structure of said vertical wall.

In testimony whereof I hereunto affix my signature.

EZRA A. WHEATON.
